UNITED STATES PATENT OFFICE.

TIRA S. STEWART, OF TERRE HAUTE, INDIANA, ASSIGNOR OF ONE-HALF TO EDWARD L. ISBELL, JR., OF TERRE HAUTE, INDIANA.

CAR-FENDER.

1,206,163.

Specification of Letters Patent. Patented Nov. 28, 1916.

Application filed March 1, 1916. Serial No. 81,440.

To all whom it may concern:

Be it known that I, TIRA S. STEWART, a citizen of the United States, residing at Terre Haute, in the county of Vigo, State 5 of Indiana, have invented certain new and useful Improvements in Car-Fenders; and I do hereby declare the following to be a full, clear, and exact description of the invention, such as will enable others skilled in 10 the art to which it appertains to make and use the same.

This invention relates to a car fender.

An object of the invention resides in the provision of a device which will stop the 15 car on which it is mounted as soon as an object is struck by the same.

A further object of the invention resides in so constructing the device that, as the car is stopped, the fender or scoop will be 20 dropped to lift the object which has been struck.

A further object of the invention resides in the provision of a device which may be easily installed on cars of the various types 25 used at present and which will be easy to control.

With these and other objects in view such as will appear as the description progresses the invention comprises the combination and 30 arrangement of parts as set forth in and falling within the scope of the appended claims.

In the drawings: Figure 1 is a side elevation of a device constructed in accordance 35 with the invention showing the same attached to a car, the parts being in such positions that the car will be permitted to advance, only a portion of the car however being shown; Fig. 2 is a similar view with 40 the parts in the positions they will occupy when the brakes are applied; Fig. 3 is a front elevation with the parts in the positions shown in Fig. 1; Fig. 4 is a similar view with the parts in the positions shown 45 in Fig. 2; Fig. 5 is a top plan view, the parts being in the positions shown in Fig. 1; Fig. 6 is a similar view the parts being shown in the positions disclosed in Fig. 2; Fig. 7 is a vertical sectional view taken longitudinally 50 of the car, and Fig. 8 is a vertical sectional view taken transversely of the car on line 8-8 of Fig. 5.

In the embodiment I have illustrated a portion of a car 1 which is supported by a

plurality of wheels 2 and driven by means 55 of a motor 3, the drive shaft of which is indicated at 4, the remainder of the motor being represented only conventionally as the specific structure forms no part of the present invention, it being understood at the outset 60 that the invention may be applied to cars irrespective of the motive power used.

The embodiment of my invention illustrated includes a frame indicated generally by the reference character 5 which frame is 65 U-shaped in form. The legs of this frame are secured to the bottom of the car in such manner that the frame protrudes beyond the front of the car, the bight portion of the frame being located in advance of the 70 car. On the end of each of the legs is an eye 6 in which eyes the side bars 7 of a fender 8 are pivotally mounted. This fender 8 is scoop-shaped and extends forwardly of the car. Pivotally secured to the 75 sides of the fender by means of eyes 9 is an upwardly extending inverted U-shaped guide 10, the legs of which extend through loops 11 formed in the legs of the frame 5 between their ends, which frame 5 is braced 80 by means of suitable brackets 12 which are formed on the legs of the frame and are secured to the dash board 13 of the car. A bell crank lever is mounted on the dash board 13 between ears 14. One arm of this 85 lever extends vertically and is provided with an operating handle 15 while the other arm 16 extends horizontally and through a keeper 17 on the bight portion of the guide 10, being slidable through the keeper and 90 being provided with an up-turned end 18 to prevent the disengagement of the keeper from the arm. By means of this bell crank lever the fender 8 may be raised.

In order that the fender may be maintained in its raised position a trip 19, which is rectangular in form is provided, which trip is hinged at its upper end as at 20 to the bight portion of the frame. Secured to this trip member 19 is an arm 21 which extends downwardly and inwardly therefrom in acute angular relation and is provided with a hook 22 on the end thereof on which hook a cam surface 23 is provided, the purpose of which will later appear. This hook 105 22 is adapted to engage the opening 24 in the forward end of the fender 8 so that the fender will be maintained in its raised po-

sition, the pull on the hook not being concentric with the pivot of the trip member 19.

In order that the fender 8 may be released when the trip member 19 strikes an object so that it will drop to the ground a U-shaped slide 25 is provided which slide is pivotally mounted on the trip member 19 by means of eyes 26 and is provided adjacent to its bight portion with loops 27 through which the legs of the frame 5 extend so that the eyes may move upon the legs to permit the movement of the trip member 19. Pivotally connected to this slide 25 at each side of the bight portion thereof are links 28 which are, at their upper ends pivotally connected to the guide 10 in offset portions thereof as at 29. Thus when the trip member 19 engages an object so that the object will strike the trip member below its pivot point the hook 22 will be disengaged from the opening 24 in the fender 8 and the fender permitted to drop. This movement of the fender will cause the slide 25 to move upon the legs of the frame 5 and lift the trip member into the position shown in Fig. 2 of the drawings. When the handle 15 of the bell crank lever aforementioned is operated to lift the fender in a manner which has been previously described, the links 28 will cause the slide 25 to move forwardly on the legs of the frame 5 and this movement of the slide will return the trip member 19 to its initial position and the hook 22 into engagement with the opening 24 in the fender 8 ready for subsequent operation.

In order that the brake which is indicated in the longitudinal sectional view by the reference character 30 may be applied to the drive shaft 4 so as to prevent the rotation of the shaft when the trip member is actuated and the fender drops, a downwardly extending arm 31 is formed on the fender and to this arm a connecting rod 32 is pivoted which rod extends and is attached to the brake 30, being passed through a guide 33. It will be seen with this attachment of the brake to the fender that when the fender drops the brake will be applied and the greater the weight of the body which strikes the fender the greater will be the force tending to prevent the advance of the car, that

is to say the greater will be the force with which the brake is applied.

From the foregoing description it will be seen that I have provided a fender which is normally held in a raised position but which when dropped will not only prevent the object which is struck by the car on which the fender is mounted from passing beneath the car, but will also apply the brakes to arrest the movement of the car. Furthermore, I have provided a controlling mechanism for this fender which will, when actuated by the body which is struck release the fender so that it will drop under the action of gravity.

While I have illustrated and described a particular embodiment of my invention I do not wish to be limited to that particular embodiment as it is obvious that numerous changes may be made in the details of construction thereof without departing from the spirit of the invention or exceeding the scope of the claims.

What I claim, is:—

1. The combination with a car having a brake, of a U-shaped frame mounted on the car and extending forwardly therefrom, a fender pivotally mounted on the frame and connected to the brake, means for raising the fender, means for maintaining it in its raised position, and means for releasing the last mentioned means whereby the fender will be permitted to drop and the brake applied.

2. The combination with a car having a brake, of a frame extending forwardly from the car, a fender pivotally mounted on the frame and connected to the brake, a trip member pivotally mounted at its upper end on the frame and having a hook thereon adapted to engage the fender to maintain the same in a raised position, manually controlled means for raising the fender and means connecting the last mentioned means and the trip member for resetting the latter upon the raising of the fender.

In testimony whereof, I affix my signature, in the presence of two witnesses.

TIRA S. STEWART.
